UNITED STATES PATENT OFFICE.

EDWARD S. HERBERG, OF ASTORIA, NEW YORK, ASSIGNOR TO BARKER BROS., INC.,
A CORPORATION OF NEW YORK.

BUFFING WHEEL.

Application filed July 20, 1927. Serial No. 207,032.

This invention relates to rotary polishing apparatus and particularly to a buffing wheel adapted to be mounted on a tapered threaded arbor to rotate therewith.

5 The object of the invention is to provide a simple inexpensive buffing wheel of this type which will be rugged and durable in service. Hitherto there has been a tendency for the threads of the arbor to wear loose in the wheel 10 so as to lose its grip thereon and the useful life of the wheel has thus been shortened.

In the buffing wheel of this invention a secure and durable grip between the tapered arbor and wheel is provided by a very simple 15 and inexpensive construction of the wheel.

In the accompanying drawings illustrating the invention.

Fig. 1 is a perspective view of the wheel;

20 Fig. 1^a is a partial sectional view showing the application of the wheel to an arbor;

Fig. 2 is a central sectional view of a wheel illustrating the modification, and

25 Fig. 3 is a face view of the wheel of Fig. 2 on enlarged scale and with the outer portion 25 of the wheel broken away.

In the wheel illustrated in the accompanying drawings a number of flexible fabric disks 5 of circular formation are packed together in a pile with a facing disk 6 on each side of flexible leather or other fibrous material. The pack with the leather disks is sewed together by the cord 7 or other fastening means passing completely through the disks and the pile 30 in a generally polygonal form concentric with the circle of the disks. This threading 7 is drawn tight so as to snugly compact the fabric and leather disks together and leave a bulge in each direction toward the center and toward the periphery as shown in Fig. 2. The 35 fabric and leather disks have central holes 8 in register at the exact center of the wheel and through these holes the inner portions of the disks are impregnated with a hardening compound, such as shellac, forming a hardened 40 core for the wheel. This hardened core is within but extends to the ring of threading 7, the fabric and leather disks thoroughly 45 absorbing the shellac to the area where they are tightly drawn together by the threading.

50 In this way there is formed a composite wheel having a core of hardened leather and fabric and continuing outward from the core

the leather and fabric disks in flexible formation. Surrounding the core and between the core and the periphery is the threading 7 55 forming a drawn compact area and acting to rigidly bind all of the parts together.

The holes 8 are about one-eighth of an inch in diameter and in the use of the wheel the tapered arbor or mandrel 10 is threaded into 60 the central opening formed by these holes, said arbor or mandrel cutting its own threads and forming its own taper in the central core. The hardened leather and fabric material of the core form a very tough and resistant combination securely holding the wheel on the arbor. The tendency of the work is to drive the wheel further and further up on the taper of the arbor but this is resisted by the hardness and toughness of the core and by 70 the tight sewing of the cord 7 holding the core against expansion or loosening in any way. At the same time the combined leather and fabric core is sufficiently yielding to accommodate itself to the mandrel and strongly grip it so that the wheel is accurately and 75 rigidly rotatable with the mandrel in service.

As indicated, in Figs. 2 and 3, the leather disks 16 may have their central holes 18 smaller than the central hole 28 of the fabric 80 disks 15. With this construction the insertion of the tapered arbor will carry in with it the overhanging portion of the leather disks so as to form an inwardly bent leather lining for the arbor hole and increasing the toughness and tightness of the grip on the arbor. 85

The buffing wheel of this invention is of very simple formation consisting of only three parts—the fabric disks, the leather disks and the cord—the hardening shellac rigidly 90 binding the central portions of the disks together in a solid mass. The disks are continuous between the hardened core and the flexible outer portion so that there is no joint or area of weakness in the transmission of 95 the rotative force. At the same time a very tough and adaptable core construction is provided giving a very tight and durable grip on the arbor.

I claim:

In a buffing wheel the combination with a pack of concentric circular disks of flexible absorbent fabric material, of concentric facing disks of smaller diameter on each side

thereof formed of fibrous flexible material stiffening medium absorbed in the absorbent adapted to absorb a stiffening medium, a materials of said disks and forming a tough ring of fastening means through all of said hardened circular core within and extend- 10 disks drawing said disks snugly together ing to said fastening means, the portion of the 5 along the line of the fastening means and ex- fabric and fibrous disks beyond said core tendsing around the axis of the wheel at a being uniformly flexible.
distance from the centre, and a hardening

EDWARD S. HERBERG.
